[57] **CLAIM**

The ornamental design for a flashlight or similar article,
as shown and described.

DESCRIPTION

FIG. 1 is a perspective view of a flashlight or similar
article showing our new design;

FIG. 2 is a top plan view thereof on an enlarged scale;

FIG. 3 is a right side elevational view thereof on an
enlarged scale;

FIG. 4 is a left side elevational view thereof on an
enlarged scale;

FIG. 5 is a bottom plan view thereof on an enlarged
scale;

FIG. 6 is a front elevational view thereof on an enlarged
scale;

FIG. 7 is a rear elevational view thereof on an enlarged
scale;

FIG. 8 is a front elevational view thereof on an enlarged
scale, the flashlight being raised by its retractable
bracket;

FIG. 9 is a right side elevational view thereof on an
enlarged scale, the flashlight being raised by its retract-
able bracket.

FIG. 1FIG. 2FIG. 3
